(57) **CLAIM**

The ornamental design for a shoe wash bag as shown and described.

DESCRIPTION

FIG. 1 is a rear, right, and bottom perspective view of a shoe wash bag, showing my new design;

FIG. 2 is a front, left, and top perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of an encircled area labeled "9" in FIG. 2.

The broken lines depict portions of the shoe wash bag that form no part of the claimed design. The dash-dot lines illustrate the boundary of the enlarged views and form no part of the claimed design.

1 Claim, 9 Drawing Sheets
